TRANSMISSION CONTROL

Sumner Bisbee Wright, South Orange, and Doren Mitchell, Martinsville, N. J., assignors to American Telephone and Telegraph Company, a corporation of New York

Application August 29, 1931, Serial No. 560,216

10 Claims. (Cl. 179—170)

This invention relates to systems for the transmission of energy. More particularly, the invention relates to telephone systems, over which are transmitted the electrical waves representing speech. With greater particularity, the invention relates to telephone circuits—especially four-wire circuits—in which transmission is controlled by switching devices responsive to energy in the transmission paths.

10. In a telephone circuit it is often desirable to maintain a normal, or non-operating, condition of disability, in order to prevent "singing". It then becomes necessary, of course, to cause the removal of this disability when speech energy is transmitted. In the case of a four-wire circuit, in which the path normally disabled is associated with a path for transmission in the opposite direction (usually through a hybrid coil connection to an extending two-wire circuit), unbalance conditions may, and usually do, result in the reflection of energy transmitted over the latter path into the former. Again, the normally operative one-way path usually has associated with it wave-responsive devices for controlling the transmission over the four-wire circuit. If this normally operative path is adapted for transmission from a link of the system which is noisy or unstable—a link which may be termed generically "mutable"—such as a radio link, which may be noisy due to static, the interfering energy may cause undesired operation of the transmission control apparatus. It is feasible to employ manually operated controls for adjusting the losses in the transmission paths and the sensitivities of the wave-responsive transmission control apparatus, with a view to reducing the chance of false operation of that apparatus, and such adjustment is usually desirable. It is important, however, especially in the case of a system including a noisy or otherwise mutable link, that further precautions be taken against undesired operation of transmission controls by interfering energy, and it is likewise important that such precautions do not involve unnecessary lowering of volume in the transmission paths.

It is proposed to disclose the applicants' invention as applied to the terminal of a four-wire circuit having a "transmitting" path adapted to transmit energy, such as that representing speech, from a two-wire circuit to a noisy link, such as a radio link, and a "receiving" path adapted for the transmission of energy from the noisy link to the two-wire circuit.

55. One of the principal objects of the invention

is the automatic adjustment of the sensitivity of the transmission control apparatus responsive to energy in the receiving path in accordance with the incoming static or other interfering energy.

Another object of the invention is the automatic adjustment of the receiving volume in accordance with the incoming static.

It will be understood that the accomplishment of the above-stated objects has the ultimate result of rendering more nearly satisfactory the operation of the wave-responsive transmission controls, including the singing suppressor control, without avoidable reduction of the volume delivered to the subscriber connected to the two-wire circuit, for instance.

The applicants, in general, utilize a "desensitizing" circuit, and by a novel arrangement of circuit elements provide for the adjustment of the "receiving" transmission control apparatus sensitivity or the adjustment of the "receiving" volume, or both, in accordance with the static or other interfering energy in the receiving path. The arrangement is such that substantially no unnecessary reduction of received volume is introduced.

The invention will be clearly understood when the following description of one desirable embodiment and the operation thereof is read with reference to the accompanying drawing, showing the circuits in diagrammatic and partly in schematic form.

With reference to the details of the drawing, there is disclosed the left-hand terminal of a four-wire circuit connecting a two-wire circuit L at the left to a noisy link (indicated) at the right. The one-way two-wire path L₁ is adapted for transmission from circuit L to the noisy link, and the one-way path L₂ is adapted for transmission from the noisy link to the circuit L. The connection between the two-wire circuit L and the four-wire circuit is made through the hybrid coil HC, associated with an artificial network the impedance of which simulates rather poorly the impedance of the line L. It will be understood that the link indicated as lying to the right of the four-wire circuit may be any mutable link in which the occurrence of interfering energy is likely. It will be well, however, to think of this mutable link as a radio link, in which static gives rise to one of the problems solved by the applicants.

In the one-way path L₁ a vacuum tube T₁ with associated elements to be discussed hereinafter, (or an equivalent device) provides a variable impedance bridged across the transmission line.

Likewise, the vacuum tube T_2 with its associated elements (or the equivalent) provides a variable impedance connected across the one-way transmission path L_2 .

5 It will be noted that the path L_1 is normally disabled at the point a for the purpose of the suppression of singing, this disability being under the direct control of a relay SS , which may be termed the singing suppressor relay. It will 10 be noted further that the path L_2 , while normally in operative condition, may be disabled at the point c by the operation of a relay ES , which may be termed the echo suppressor relay. The operation of relays SS and ES is indirectly 15 controlled by the amplifier-detector AD_1 associated with the path L_1 at point b . It should be noted further that an amplifier-detector AD_2 is connected across the line L_2 at point d and controls switching apparatus to be discussed 20 hereinafter.

The regular or normal control of volume in the transmission paths L_1 and L_2 is specifically disclosed as involving the manual operation of potentiometers P_1 and P_2 , tied together for simultaneous operation as indicated in the drawing. It should be noted at this point that the 25 amplifier-detector AD_1 responds to energy in path L_1 at point b , and that amplifier-detector AD_2 responds to energy in path L_2 at point d .

30 Let it be assumed that a talker of weak voice is connected to the line L . Since the path L_1 , over which the voice waves are to travel, is under the normal disability at point a , it now becomes necessary to remove this disability by the 35 operation of relay SS . It is also desirable that the opposite path L_2 be disabled at point c for the suppression of echoes by the operation of relay ES . It will be noted that when amplifier detector AD_1 operates, a relay S , having its winding included in the output circuit of the amplifier-detector operates to connect battery to the windings of relays SS and ES and thus to cause the operation of these two relays. Accordingly, 40 in the case of a weak talker connected to the line L , it may be necessary to decrease the loss introduced in path L_1 by the apparatus including the vacuum tube T_1 . For this purpose the potentiometer arms are turned in a clockwise direction. This operation of the potentiometer P_1 45 increases the normally considerable negative biasing voltage impressed on the grid of tube T_1 and raises the tube impedance bridged across the path L_1 . This operation, of course, results in decreasing the loss introduced in the path L_1 , and this adjustment permits the response of amplifier-detector AD_1 and the associated relays to the comparatively weak voice energy applied. The path L_1 is now clear at point a , and the opposite path L_2 is blocked at point c .

50 Since the two potentiometer arms are tied together, the operation of the devices not only adjusts the setting of potentiometer P_1 to change the loss in path L_1 but also adjusts the setting of potentiometer P_2 . When the arm of potentiometer P_2 is turned in a clockwise direction, the 55 normally excessive negative bias impressed on the grid of tube T_2 from battery B_2 is reduced. By the time that the loss in path L_2 is sufficiently lowered to give the likelihood of false 60 operation of amplifier-detector AD_1 by energy originating in path L_2 which is too weak to operate relay S' and is reflected back over path L_1 from the two-wire circuit L , the impedance of tube T_2 bridged across the path L_2 is appreciably 65 lowered, and increased loss is introduced into 70

the receiving path. This operation, it will be understood, prevents false operation of amplifier-detector AD_1 by reflected energy.

It will be noted that filter F_1 is interposed between the potentiometer P_1 and tube T_1 and that a filter F_2 is interposed between potentiometer P_2 and the tube T_2 . These filters serve to prevent clicks in the telephones connected to the transmission lines, as a result of sudden changes in the settings of the potentiometers.

10 It will be noted that a polar relay S' , with two windings, has its right-hand winding w_1 connected in the output circuit of amplifier-detector AD_2 and that this winding is arranged to attract the relay armature to its front contact and thus open the output circuit of amplifier-detector AD_1 . The left-hand winding of this relay w_2 is arranged to exert a force in opposition to winding w_1 , that is, to hold the armature of relay S' on its back contact and thus to maintain the closed condition of the output circuit of amplifier-detector AD_1 . When energy comes in over the path L_2 and passes the point c , it normally causes the operation of amplifier-detector AD_2 , which in turn causes the 15 operation of relay S' and opens the output circuit of amplifier-detector AD_1 . This operation prevents the operation of relay S , and consequently the operation of relays SS and ES , in response to later arriving energy in path L_1 . It 20 will be understood, however, that without further provision this relay S' is subject to undesired operation by noise or other interfering energy in path L_2 as well as to the desired operation by voice energy in this path.

25 It will be understood, further, that noise energy coming in over the path L_2 may reach path L_1 by reflection from circuit L and may cause false operation of the amplifier-detector AD_1 and the relays controlled thereby.

30 For the purpose of preventing the above suggested undesirable operations, the applicants employ a proportional desensitizing circuit together with other apparatus now to be discussed.

35 The proportional desensitizing circuit comprises vacuum tubes T_3 , T_4 , T_5 , T_6 and T_6' and various resistances and capacities. The principle of this circuit and the operation thereof are clearly disclosed and fully discussed in United States Patent No. 1,772,551 to Mitchell and Silent, and accordingly a detailed description or discussion herein is unnecessary. It is sufficient to state that the desensitizing circuit 40 distinguishes between the rapidly fluctuating voice energy and noise energy or the like, which is of comparatively sustained level. The circuit operates to prevent any appreciable effect from the voice energy but to produce an appreciable effect in response to the energy of comparatively sustained level. This effect is the variation 45 of the plate current in the tubes T_6 and T_6' (which are connected in parallel) in accordance with and in proportion to the energy of 50 sustained level.

55 It will be noted that the winding w_2 of relay S' is connected in the plate circuit of the vacuum tube T_6' of the desensitizing circuit. Thus when noise energy, or the like, comes in over the path L_2 , a bias is gradually built up through energization of winding w_2 , and this bias is sufficient to prevent the operation of relay S' due to energization of winding w_1 connected in the output circuit of amplifier-detector AD_2 . In other words, the relay S' is desensitized in accordance with the noise energy or other energy 60

of sustained level to the point which prevents its operation by noise or the like, and the consequent undesired opening of the output circuit of amplifier-detector AD₁.

5 It will be understood that this reduction of the sensitivity of relay S' carries with it the penalty of the likelihood of false operation of the transmitting relays SS and ES by reflected energy of sustained level in path L₁, since this 10 energy may have passed point d in path L₂ without operating relay S' and in its reflected form may operate amplifier-detector AD₁. With this difficulty in their minds, the applicants provide for auxiliary adjustment of the loss introduced 15 in path L₂ by tube T₂. It will be noted that a resistance R is included in the plate circuit of tube T₆ of the desensitizing device. This resistance may be variable to give a suitable initial adjustment. As the energy of sustained 20 level causes the operation of the desensitizing circuit, a voltage is built up across the resistance R (or the effective portion of this resistance) which tends to cancel the negative voltage applied to the grid of tube T₂ by the battery B₂. 25 This auxiliary voltage reduces the impedance of the tube T₂ and increases or tends to increase the loss introduced in path L₂. Thus, if the potentiometer arms are turned in a clockwise direction to adjust for a weak talker, the volume 30 in path L₂ is lowered sooner if the noise coming in over path L₂ is high than if this noise is comparatively low. It will be noted, however, that no penalty is attached to a strong talker connected to circuit L, since for such a talker the 35 proper setting of potentiometer P₂ (and P₁) keeps the cancelling voltage applied to the grid of the tube T₂ low enough to render it ineffective against the normal negative biasing voltage on the grid.

40 While the invention has been disclosed specifically for the purpose of illustration, it is to be understood that such disclosure does not limit the scope of the invention, which is determined by the appended claims.

45 What is claimed is:

1. In a system for the transmission of energy, a transmission path, control means in said path for introducing a variable loss therein, and means responsive to energy of comparatively 50 sustained level such as noise in said path, which energy may be in a frequency range including the voice range, for adjusting said control means to vary the loss introduced thereby in said path, said last-stated means being substantially unresponsive to energy of rapidly fluctuating level 55 such as speech.

2. In a system for the transmission of energy, a transmission path, control means in said path for introducing a variable loss therein, and 60 means responsive to energy of comparatively sustained level such as noise in said path, which energy may be in a frequency range including the voice range, for adjusting said control means to vary the loss introduced thereby in said path 65 in proportion to the magnitude of said energy, said last-stated means being substantially unresponsive to energy of rapidly fluctuating level such as speech.

3. In a system for the transmission of energy, 70 two paths adapted for transmission in opposite directions, means for normally disabling the first path, clearing means responsive to energy in said first path for removing the normal disability therefrom, control means normally responsive to energy in the second path for prevent-

ing the removal of said disability on said first path, and means responsive substantially only to energy of comparatively sustained level in said second path for desensitizing said control means.

4. In a system for the transmission of energy, 5 two paths adapted for transmission in opposite directions, means for normally disabling the first path, transmission control means responsive to energy in said first path for removing the normal disability therefrom and disabling the second path, control means normally responsive to energy in said second path for preventing the operation of said transmission control means, and means responsive substantially only to energy of comparatively sustained level in said 10 second path for desensitizing said later named control means.

5. In a system for the transmission of energy, 20 two paths adapted for transmission in opposite directions, gain control means in each path for introducing a variable loss therein, means for normally disabling the first path, clearing means responsive to energy in said first path for removing the normal disability therefrom, control means responsive to energy in the second path 25 for preventing the removal of said disability on said first path, and means responsive substantially only to energy of comparatively sustained level in said second path for desensitizing said control means and for adjusting the operation 30 of the gain control means in said second path.

6. In a system for the transmission of energy, 35 two paths adapted for transmission in opposite directions, gain control means in each path for introducing a variable loss therein, means for adjusting the setting of said gain control means, means for normally disabling the first path, transmission control means responsive to energy in said first path for removing the normal disability therefrom and for disabling the second path, control means normally responsive to energy in said second path for preventing the operation of said transmission control means, and means responsive substantially only to energy of 40 comparatively sustained level in said second path for desensitizing said last-named control means and for introducing an auxiliary adjustment of the setting of the gain control means 45 in said second path.

7. In a system for the transmission of energy, 50 a four-wire circuit including a first path adapted to transmit energy to a mutable link of the system and a second path adapted to receive energy from the mutable link, means for normally disabling said first path, clearing means responsive to energy in said first path for removing the normal disability therefrom, and control means associated with said second path for preventing the operation of said clearing means, said control means being responsive to the energy in said 55 second path which is transmitted over the system for the production of the desired over-all effect but unresponsive to interfering energy received in said second path from the mutable link.

8. In a system for the transmission of energy, 60 a four-wire circuit including a first path adapted to transmit energy to a mutable link of the system and a second path adapted to receive energy from the mutable link, means for normally disabling said first path, transmission control means responsive to energy in said first path for removing the normal disability therefrom and for disabling said second path, and control means associated with said second path for pre- 65

venting the operation of said transmission control means, said control means being responsive to the energy in said second path which is transmitted over the system for the production of the desired over-all effect but unresponsive to interfering energy received in said second path from the mutable link.

9. In a system for the transmission of energy, two paths adapted for transmission in opposite directions, the first of said paths being subject to the reflection thereover of energy normally transmitted over the second path, transmission control apparatus responsive to energy in said first path, gain control means in each of said paths adapted for simultaneous adjustment, and means responsive to energy of comparatively sustained level such as noise in said second path for introducing an auxiliary adjustment of the gain control means in said second path without changing the gain in said first path, said noise-responsive means being substantially unresponsive to energy of rapidly fluctuating level such as speech.

10. In a system for the transmission of energy, a first transmission path adapted to transmit energy to a mutable link of the system and a second transmission path adapted to receive energy from the mutable link, said first path being subject to the reflection thereover of energy normally transmitted over said second path, transmission control apparatus responsive to energy in said first path, gain control means in each of said paths adapted for simultaneous adjustment, and means responsive to energy of comparatively sustained level such as noise transmitted over said second path from the mutable link for introducing an auxiliary adjustment of the gain control means in said second path without changing the gain in said first path, said noise-responsive means being substantially unresponsive to energy of rapidly fluctuating level such as speech received in said second path from the mutable link.
